UNITED STATES PATENT OFFICE.

HORACE M. CAKE, OF WASHINGTON, DISTRICT OF COLUMBIA.

PACKAGE-TIE.

1,020,963.

Specification of Letters Patent. Patented Mar. 26, 1912.

Application filed January 14, 1911. Serial No. 602,591.

To all whom it may concern:

Be it known that I, HORACE M. CAKE, a citizen of the United States, a resident of the city of Washington, in the District of Columbia, have invented certain new and useful Improvements in Package-Ties, of which the following is a specification.

This invention relates broadly to package ties and, specifically to a type of package tie 10 wherein the tying is accomplished by means of a metallic member attached to a flexible cord.

The principal object of this invention is to construct a package tie in such manner 15 that packages may be quickly and securely tied and may with equal quickness be untied without cutting or destroying the flexible cord.

Another object of this invention is to construct a package tie formed of symmetrical proportions and being adapted to receive advertising matter upon a portion of its 20 surface.

Another object of this invention is to construct a symmetrical metallic package tie 25 which will automatically grip a flexible cord when the cord has been drawn to a predetermined degree of tension.

A further object of this invention is to 30 construct a metallic package tie in such manner that the automatic turning of the package tie during tensioning of the cord causes the cord to automatically leave a slipping surface and drop into a wedge slot, 35 thus automatically tying the package.

Still other and further objects of this invention will in part be obvious and will in part be pointed out in the specification hereinafter following, and by reference to the 40 accompanying drawings in which like numerals are used to indicate like parts throughout the several figures thereof.

Figure 1 is a detail plan view of the package tie. Fig. 2 is a detail view of one of the slipping surfaces and accompanying wedge slots. Fig. 3 is a view showing the first step of operation in tying a rectangular package with the package tie. Fig. 4 is a view showing the second step in tying a rectangular package. Fig. 5 is a view showing the third step in the operation of tying a rectangular package. Fig. 6 is a view showing the package in the last and completed step of operation of tying the package and illustrates a package in its tied condition.

Referring to the drawings and more specifically to Fig. 1, a package tie 1 comprises a piece of sheet metal whose exterior contour is substantially that of a portion of a circle. A back opening 2 is formed between projections 4 and 5, the said opening being adapted to act as a slipping block or surface for bending a portion of a flexible cord 6 in making the cross cord when tying a package. The outer ends of the package tie 1 are formed into claws 7 and 8, which are symmetrical in contour and which are provided at their base with wedge slots 9 and 10. The metal between the wedge slots 70 and the periphery of the claw members may be corrugated as at 11 and 12, in order to stiffen the metal and prevent the wedge slots from weakening the claw members. Each of the claw members 7 and 8, are 75 provided on their interior edges with depressions 14 and 15 which are formed with smooth slipping surfaces, for reasons which will hereinafter be explained in describing the operation of the tie. Low projections 16 and 17 are provided between the depressions 14, 15 and the wedge slots 9, 10 respectively. The major axis of the wedge slots 9 and 10 are arranged to lie upon lines A—A, B—B, 80 which lines are substantially at right angles to each other and which cross each other at the middle point of the back opening 2. These lines represent the direction which the members of the flexible cord will assume when the tie is in position upon a 85 square package.

For certain purposes, particularly for tying cylindrical packages, it may be found convenient to make the entire package tie 95 from flexible sheet metal without corrugating the portions between the wedge slots and the periphery of the tie, in order that the tie may conform itself to the contour of a cylindrical package. Since the tie is adapted to be formed of sheet metal, flat portions thereof, for example, the part lying between the back opening and the periphery, may be utilized for advertising space.

The operation of the package tie, as illustrated in Figs. 3 to 6 inclusive, is substantially as follows:—The first operation in binding a package with this invention, is to insert one end of a cord in either of the wedge slots 9 or 10, for example 9. The cord is then brought around the package 100 and through the back opening 2, as is illustrated in Fig. 3. The cord is drawn taut 105 and the package is tied.

and around the package in a direction substantially at right angles to the original direction of the cord, as is illustrated in Fig. 4, and the cord is then looped over the slipping surface 15. It will be noted by referring to Fig. 4, that the package tie device is drawn to one side of the package and the wedge slots 9 and 10 are substantially in line with the transverse axis of the package. After the string has been looped over the slipping surface 15, as is illustrated in Fig. 5, and pulling pressure is brought upon the loose end of the string, it will be noted there is a tendency to cause the package tie to turn. The tighter the string is drawn the more the turning of the tie until it has turned sufficiently for the cord to slip over the projection 17 and drop into the wedge slot 10. Immediately as the flexible cord drops into the wedge slot 10 the package is securely tied. It will be noted that the tie now occupies a position, as shown in Fig. 6, in which the wedge slots 9 and 10 are alined with the longitudinal and cross ties respectively. A particular feature of novelty in this tie is the automatic manner in which the tie turns to grip the cord after it has been drawn to a sufficient degree of tightness. As has been hereinbefore explained, it will be noted that as the free end of the cord is being drawn up, the package tie moves from its position near the side edge of the package over toward the center of the package and undergoes a translatory turning movement until it has turned sufficiently to allow the cord to slip into the wedge slot. When it has turned a sufficient amount to permit the cord to slip into the wedge slot, the package cords will be found to be of a proper degree of tension to se-

curely hold the binding cord upon the package.

As many and obvious changes could be made in the above described structure without departing from the scope of the claims, I desire that it shall be understood that the disclosure and construction shall be taken as illustrative and not in a limiting sense. I also desire it to be understood that the language used in the claims is intended to cover all generic and specific features of this invention and all statements of the scope of the invention which as a matter of language might fall therebetween.

Having thus described my invention what I claim is:—

1. A package tie comprising a body portion having two adjacent terminal members at one side thereof, one of said terminal members being provided with means for securing a cord, the other of said terminal members having a smooth concave inner edge and a wedge slot adjacent thereto, and the body portion being provided with a smooth curved inner edge substantially opposite the terminal members.

2. A package tie comprising a body portion having two adjacent terminal members at one side thereof, said terminal members being provided with smooth concave inner edges, wedge slots adjacent said edges, the body portion being provided with an opening in the side opposite the terminal members and having a smooth curved inner edge along said opening facing the concave edges of the terminal members.

HORACE M. CAKE.
